UNITED STATES PATENT OFFICE

CARL MARISCHKA, OF VIENNA, AUSTRIA

COMBINED GAS AND STEAM GENERATOR

Application filed July 3, 1925, Serial No. 41,286, and in Austria and Germany July 5, 1924.

In gas generators provided with steam-producing jackets, briefly called generator-boilers, it is well known to utilize the heat contained in the gases produced for the production of steam in the generator itself, by passing these gases through an outer heating jacket surrounding the boiler and immediately connected with the generator shaft. Constructions of this kind of generator-boilers are for example disclosed in Austrian Patent No. 52,150; the gas escaping from the generator shaft either passes through heating tubes into the external heating jacket, or in cases where upper and lower boilers are provided the gas passes in contact with water tubes into the external heating tubes in order here to deliver a still further amount of its heat.

These well known constructions however are no longer adapted for use when different gases are produced in one and the same generator in alternating sequence or in intermittent periods (water gas production), and the problem is to utilize in the generator itself for the production of steam the latent heat of the combustible gases obtained in the first period of the water gas production. This latent heat is only liberated when a combustion of the gases is brought about by the addition of air. Then the heat liberated in the combustion gases is made use of; the utilization is effected, as is well known, in such a manner that the "blow" gases generated from a water gas generator in the first period by a hot air blast are passed into a combustion chamber (heat accumulator, super-heater or the like) adjoining the generator, and there are burned mixed with air, whereupon the hot gases given off flow through a boiler to there deliver up their heat for the purpose of producing steam. Also the water gas generated in the second period can in some cases be passed through a combustion chamber serving as a heat-accumulator, without in this case being subjected to combustion, as is obvious. The water gas takes up heat in the heat-accumulator, in order to utilize the same for the generation of steam when subsequently flowing through the boiler. If it is not desired to

pass the water gas through the heat-accumulator, the heat stored in the accumulator during the hot blowing can be utilized during the gas-generating period by passing the steam, required in the generator for the generation of water gas, through the heat-accumulator and there subjecting it to a drying or superheating treatment.

Though the present invention utilizes these well known features, it constitutes an important advance in the art in that the boiler separated from the generator is dispensed with, while on the other hand the combined gas and steam producer is operated in such a manner that notwithstanding the presence of a combustion chamber serving as a heat-storer, and the corresponding passage of the hot blow gases and also of the water gas, the greatest possible utilization of the combustible gases contained in the hot blow gases is assured. Owing to the omission of a boiler separated from the generator in a water gas installation with utilization of the hot blow gases, both the cost and the floor space required for such an installation are considerably reduced, and in addition, a better thermal effect is ensured by the reduction of the heat radiating surfaces.

The invention is illustrated in the accompanying drawings, in which Fig. 1 shows in a diagrammatic elevation the general arrangement of a gas producing plant designed in accordance with this invention; Figs. 2 and 3 are respectively vertical and horizontal sectional views of a combined gas and steam generator; Figs. 4 and 5 are similar views to Figs. 2 and 3 showing a modified gas and steam generator. Figs. 6 and 7 are also similar views to Figs. 2 and 3 showing a further modification.

The gas generator, of any desired form of construction, and having a steam-generating jacket, is arranged, contrary to the construction shown in the above said Austrian patent specification No. 52,150, in such a manner that the shaft chamber *a* is completely separated from the outer heating jacket *b* surrounding the boiler *c*, so that no direct passage of the gas from the shaft chamber of the generator into the heating jacket chamber is possible.

A connection is however provided between the chambers *a* and *b* in such a manner that at the top and at the bottom of the shaft chamber *a* a combustion chamber *g* is connected therewith by the pipes *e* and by means of the connection *f*, the said combustion chamber *g* being formed as a heat-storer, superheater and the like, and being connected through the pipe *h* by means of the connection *d* with the heating jacket *b*. The pipes *e* and *h* are also directly connected with one another in a manner cutting out the combustion chamber *g*. The cut-off devices *i* provided in both pipes make the different connections feasible. At the part of the pipe leading under the grid a safety valve *p* is arranged. From the heating jacket *b* the cooled combustion gases pass through the connections *j* into a pipe or conduit *k* having two branches and provided with cut-off devices *i*, one branch of the pipe leading to the cooler, washer and gas container, and the other branch terminating under the chimney. The blast pipe *e'* provided with cut-off devices *i'* and connected to a fan (not shown) serves for the introduction of the blast at the bottom of the generator shaft when hot blowing and for the purpose of effecting the combustion of the hot blow gases in the heat-storer *g*. The steam escaping from the steam chamber of the generator boiler is passed directly into the generator shaft at the top or at the bottom through the pipe *n* for the purpose of generating water gas, or it is first passed by means of the pipes *n'* through the combustion chamber *g*, where the steam is superheated. The desired vapour paths are obtained by appropriately adjusting the cut-off devices *m* provided in the steam pipes *n*, *n'*. All or only part of the steam produced by the apparatus may be used to make water gas. Ordinarily, however, less than one-half of the total amount of steam produced is used for making water gas and the remainder is used for other purposes.

The air coming from the fan is forced through the pipe *e'* under the grid and through the incandescent fuel in the shaft chamber, the said fuel thereby brought to a white heat. The combustible hot blow gases produced in this first period in the shaft escape through the pipe *e* connected to the generator roof, and by appropriate adjustment of the valve *i* can be passed into the heating jacket *b* either by way of the combustion chamber *g* or direct. From the jacket *b* the gases escape through the pipe *k* into the chimney. In case the gases are passed through the combustion chamber *g*, air is introduced into the latter from the pipe *e'* whereby the combustion of the hot blow gases and the heating of the combustion chamber takes place. The hot combustion gases on passing through the heating jacket *b* deliver their heat to the boiler for the purpose of increasing the steam generation. In case the

combustion chamber *g* is not employed during the first period of the water gas production (with appropriate adjustment of the cut-off devices) the gas coming from the shaft chamber through the pipes *e* and *h* and flowing into the heating jacket *b* only deliver their sensible heat to the said heating jacket. 70

By appropriate adjustment of the cut-off devices *m* in the steam pipe *n*, the steam can be passed during the second period into the hot blown fuel both from below through the grid and from above from the generator roof. When gas is produced at the bottom, the water gas is passed from the shaft chamber through the pipe *e* connected to the generator roof, and, when gas is produced at the top, through the pipe *e* connected below the grid. 75

The water gas may now be passed into the jacket *b* in either of the two ways of the blow gases of the first period, i. e., through the pipe connections *d*, or by a circuitous path by way of the combustion chamber *g*. In this case naturally no air must be introduced into the combustion chamber. The water gas in the chamber *g* absorbs the heat stored in the first period transmitting it through the pipe *h* to the heating jacket *b*. In the latter *b* only the sensible heat is taken up from the water gas, which heat is naturally greater when the water gas passes through the combustion chamber *g*. If the water gas is not passed through chamber *g*, the heat stored in the first period can then be utilized in the second period, in such a manner that the steam necessary for the water gas generation and coming from the steam generating chamber of the generator is passed, by an appropriate adjustment of the valve *m*, through the chamber *g* before its introduction into the shaft chamber *a* of the generator, and is superheated in the said chamber *g*. The operation of the first period requires as a rule from 1 to 2 minutes and that of the second period from 4 to 6 minutes. 90

For taking up the heat which is introduced into the heating jacket *b* either with the combustion gases coming from the combustion chamber *g* (Fig. 1) or with the operating gases (water gas), an appropriately large heating surface can be provided within heating jacket *b*. In the combined gas and steam generator shown in Figs. 2 and 3 tubes *r* are for this purpose provided within the chamber enclosed by the heating jacket *b*, the bent ends of which tubes lead at different levels into a chamber *c* of the generator filled with water. The tubes arranged in this case vertically can also have a sloping position or they can be arranged in the form of spirals, in which case the inlet openings of the bent pipe ends are not disposed vertically over one another but (contrary to the illustration) are located in two different vertical planes. By this arrangement also the total heating surfaces can be increased, with the same num- 100

ber of tubes and with the tubes having the same diameters.

In the modification shown in Figs. 4 and 5 vertically arranged straight tubes *s* are provided in the jacket *b* the ends of which tubes are set in ring shaped bases *o*, which are arranged around the part of the chamber *c* filled with water, and being of a smaller diameter so as to allow the arrangement of said bases, which cut off the upper and lower wider parts of the chamber *c*.

The combustion chamber *g* (heat-storer, superheater, or the like) shown in Fig. 1 can be combined with the gas and steam generator according to the present invention. In that case, a lattice work or screen *p* of fireproof material can be provided as shown in Figs. 6 and 7 within the chamber surrounded by the jacket *b*. The jacket then constitutes at the same time the combustion chamber, the pipes for combustion air and steam being assumed to be connected to the said jacket *b*; the gas obtained in the first stage of the process, instead of being burnt in a special combustion chamber *g* as above described (Fig. 1) is now burnt within jacket *b* and the heat storer arranged in the jacket chamber gives off the stored heat by radiation to the chamber *c* in the second stage of the process. The heat-storer can in this case, too, be utilized in the second stage of the process for the purpose of drying and superheating the steam necessary for the gas production by passing the steam through the jacket.

What I claim is:

1. A combined steam and water gas generator comprising a gas generator shaft, a boiler chamber enclosing a portion of said shaft, a jacket forming a heating chamber enclosing a portion of said boiler chamber, a combined combustion chamber and heat storer, pipe connections from the top of said generator shaft to said combustion chamber and to said heating chamber and to the bottom of said generator shaft and from said combustion chamber to said heating chamber, valves for controlling the flow of gases through said pipe connections so that gases from the generator shaft may be directed through the combustion chamber and thence into the heating chamber or directly from the generator shaft into the heating chamber, valve controlled pipes for supplying an air blast either to said generator shaft or to said combustion chamber, valve controlled pipe connections for directing steam from said boiler either directly into the top or the bottom of said generator shaft or from the boiler first into the combustion chamber and thence to either the top or the bottom of said generator shaft, and an outlet from said heating chamber.

2. In a combined steam and water gas generator, a generator shaft, a boiler chamber surrounding said generator shaft, a heating jacket surrounding said boiler chamber, and

tubes disposed entirely within said heating chamber and connected at their ends with said boiler chamber.

3. In a combined steam and water gas generator, a generator shaft, a boiler chamber surrounding said generator shaft, a heating jacket surrounding said boiler chamber, the outside wall of said boiler chamber being stepped inwardly within said heating chamber, and tubes disposed within said heating chamber and connected through the ends of the stepped portion of said boiler wall with the boiler chamber.

In testimony whereof I have signed my name to this specification.

CARL MARISCHKA.
